UNITED STATES PATENT OFFICE.

JAY BENJAMIN FRANKLIN SHOWALTER, OF LOMAX, ILLINOIS.

GATE.

1,233,719.

Specification of Letters Patent. Patented July 17, 1917.

Application filed October 9, 1916. Serial No. 124,640.

To all whom it may concern:

Be it known that I, JAY B. F. SHOWALTER, residing at Lomax, in the county of Henderson and State of Illinois, have invented 5 a new and useful Gate, of which the following is a specification.

This invention more particularly has reference to farm or roadway gates and primarily has for its purpose to provide an 10 improved form of gate of the general type stated, of a strong, durable and relatively light construction, including a special design of bracing elements that provide for withstanding such jars or weights that roadway gates are usually subjected to.

Another object of my invention is to provide, in a farm gate construction of wood or metal, or a combination of both, in which is included an improved system of bracing, 20 so distributed that the body bracing means is divided into sections, each brace in the same, or in opposite directions, and each, while forming an independent bracing section, being comparatively so arranged to form 25 a perfect whole for effectively equalizing such strains, jars or weights, that might be suddenly applied against the gate by stock jumping on to it or from other causes.

Again, my invention in its more complete 30 nature, embodies an improved construction of parts composed of wood or metal, or both, and including an improved system of bracing that divides it into a plurality of independent bracing sections, each being a complete 35 independent system of bracing, and the several sections so combined whereby they form a continuous bracing system that makes the sagging of the gate practically impossible and prevents it from breaking 40 down from such jars, strains or weights to which roadway gates are usually subjected.

With other objects in view that will hereinafter appear, my invention consists in the peculiar construction and novel combination 45 of the parts to be hereinafter explained, specifically pointed out in the appended claims and illustrated in the accompanying drawings, in which—

Figure 1 is a perspective view that illustrates a perfect form of my improved gate, and in this form, the bracing elements are shown one set applied to each side of the gate.

Fig. 2 is a cross section thereof taken on 55 the line 2—2 on Fig. 1.

Fig. 3 is a side elevation that shows a

modified form of my improved gate herein-after particularly referred to, and

Fig. 4 is a side elevation of another modification of my improved gate herein-after 60 also explained.

In carrying out my invention, the gate body includes the usual horizontal rails 1, which may be of wood or metal, and these are joined by a series of vertical brace bars 65 2, preferably metal, either flat or angle iron.

Each pair of brace bars 2 divide the gate body into sections and, in the preferred form, as shown in Fig. 1, the gate body is illustrated as divided off into three sections. 70

Each of the sections is braced by a diagonal brace bar 3 which may be wood or a flat or angle iron bar and, the said independent diagonal brace bar 3, has its upper end secured at the upper end of one of the vertical bars 2 and preferably located between the said bar 2 and the upper rail 1, its lower end being similarly connected to the lower end of the next adjacent vertical brace bar 2 and the lowermost rail, the several brace 80 bars and the rail being secured by bolt and nut connections indicated by 4 and 5 in Fig. 2, so that any of the rails or boards that may become broken or worn out may be readily removed and a new board or rail 85 substituted therefor.

6 designates a master brace bar of flat or angle metal, and the said bar, herein-after termed the gate diagonal, extends the full length of the gate body from the lower end 90 of the vertical brace bar at one end to the top of the vertical brace bar at the other end and in crossing from one end of the gate body to the other, the said bar 6, is preferably secured at its upper and lower ends 95 between the end brace bars 2 and the upper and lower rails, passed under the intermediate brace bars 2 and over the individual diagonal brace bars 3—3, the said diagonal brace bar 6 being secured at points between 100 its ends by the bolt and nut connections, as shown.

By reason of arranging the brace bars in connection with the rails 1, as shown and described, each of the brace sections, contains, as it were, three rightangle bracings and two acute angle bracings, the right angle bracing portions being one, x , at the top; one, y , at the bottom; and one, z , at the bottom between the upright bars 2 and the gate diagonal 6, it being also apparent from the drawings that the several sections con- 105 110

stituting the gate body as a whole, are provided with supplemental right angle bracings, one *a* at the top by the brace bars 2 and the diagonal 6, and at the bottom *b* between the said bars 2 and the aforesaid diagonal 6.

While I prefer to form my improved gate as shown in Fig. 1, since the form shown in the said figure is the strongest 10 and most complete form of my improved gate structure, the bracing elements on one side of the rails may be omitted.

Fig. 2 shows substantially the same construction of the gate shown in Fig. 1 except 15 that the bracing is on one side and only two independent bracing sections is provided and Fig. 4 shows a structure similar to Fig. 3 but further modified, since only one independent brace section is employed.

From the foregoing description taken in connection with the drawings, the complete construction and the advantages of my invention will be readily apparent.

By reason of constructing the gate with 25 the bracing elements arranged to divide, as it were, the bracing system into three distinct sections, each in itself embodying a complete bracing system and all of the system sections cooperatively combined as 30 shown and described, a system of bracing in gate structures of the general character stated is developed, on either one of both sides of the gate, that may form a perfect whole by continuing the bracing into and 35 through each separate section, or be discontinued without effecting the support for the last or remaining ones of the several system sections.

One essential advantage attained in my 40 improved gate structure is, that with the bracing system extended through the entire length of the gate, the same forms a positively rigid gate of great strength and, since the bracing is composed of systems of 45 rightangled and acute angled bracing, rein-

forced by a coöperating diagonal bracing throughout the entire gate, the gate structure is such that it will effectively withstand all strains incident in the use of farm or roadway gates.

50

What I claim is:

1. A gate comprising a series of horizontal rails, vertical end braces connecting the rails, at least one intermediate vertical brace connecting the rails whereby the gate 55 body is formed into a plurality of sections, a diagonal brace connecting the rails and extending from one extremity of an end brace to the diagonally opposite extremity of the next adjacent intermediate brace, and a master diagonal brace extending from one corner of the gate as a whole to the diagonally opposite corner of the gate as a whole, said master diagonal brace being secured to said horizontal rails and to 60 said first mentioned diagonal brace, substantially as shown and described.

60

2. A gate comprising a series of horizontal rails, bracing elements mounted on one or opposite sides of the said rails, the bracing elements on the opposite sides being of like structure and each comprising vertical braces at the ends of the rails, at least one other vertical brace located between the vertical braces at the ends whereby the 70 body of the gate is divided into independent bracing sections, a diagonal brace bar for each of said bracing sections connected at the opposite ends to the opposite adjacent vertical brace bars and a supplemental diagonal brace bar that extends the full length of the gate and coacts with the vertical end bars and the diagonal brace bars of the section whereby to provide three rightangled bracings and two acute angled bracings in 75 each of the said bracing sections and means for securing the several bracing elements and the rails in rigid connection.
